DESIGN FOR A CREAM JAR

Charles S. Gage, Tarrytown, N. Y., assignor to
Lentheric Incorporated of New York City, New
York, N. Y., a corporation of New York

Application April 21, 1933, Serial No. 47,854

Term of patent 14 years

To all whom it may concern:

Be it known that I, CHARLES S. GAGE, a citizen of the United States, residing at 300 South Broadway, Tarrytown, New York, have invented a new, original, and ornamental Design for a Cream Jar, of which the following is a specification, reference being had to the accompanying drawing, forming a part thereof.

In the drawing of the cream jar:

Figure 1 is a top plan view of a cream jar showing my new design; and

Figure 2 is a side elevation thereof.

In Figure 2, the curved white line in the middle and the short straight white line extending therefrom are a part of the design, but the re-

maining white areas are high lights, and not a part of the design.

The dominant feature of the design consists in a jar having a conventional body and a conventional flanged lid, both of substantially the same color, and on the top of the lid a triskelion of a contrasting color, comprising slender arcuate branches, and on the flange of the lid three slender straight lines of substantially the same contrasting color, extending vertically from the ends of said branches respectively.

I claim:

The ornamental design for a cream jar substantially as shown and described.

CHARLES S. GAGE.
